UNITED STATES PATENT OFFICE.

HANS LUTZ, OF ELMIRA, NEW YORK, ASSIGNOR TO THE WILLYS-MORROW COMPANY, OF ELMIRA, NEW YORK, A CORPORATION OF OHIO.

GRINDING MACHINE.

Application filed August 30, 1920. Serial No. 406,969.

To all whom it may concern:

Be it known that I, HANS LUTZ, a citizen of the United States, residing at Elmira, county of Chemung, State of New York, 5 have invented certain new and useful Improvements in Grinding Machines, of which I declare the following to be a full, clear, and exact description.

The present invention relates to grinding 10 machines and is particularly adapted for grinding rollers either of the straight or tapered type.

The construction of the present machine is similar in some respects to the machines 15 shown and described in my co-pending applications filed May 29, 1920, and bearing Serial Numbers 300,712 and 300,713, and the improvements herein relate more particularly to the mechanism employed for 20 supporting and retaining the work as well as in the manner of mounting and moving the upper and lower members between which the objects are ground.

One object of the invention is to provide 25 an improved machine of the character described which is of simple construction and efficient in operation.

A further object of the invention is to provide a pair of eccentrically mounted and 30 driven members which are adapted to contact with the opposite sides of the objects to be ground with improved means for retaining said objects between said members.

A further object of the invention is to 35 provide improved mechanism particularly adapted for grinding tapered rollers comprising upper and lower members, one of which is adapted to carry a work retaining member and to move it in a path eccentric 40 to the path of movement of the opposite member.

Further objects of the invention relate 45 to the provision of improved instrumentalities and devices for securing a proper operation of the various mechanisms employed to effect the grinding of the work in the most proficient and economical manner.

The objects of the invention are accomplished in one instance by the devices and 50 means described in the following specification, but it is evident that the same may be varied without departing from the scope of the invention as pointed out in the appended claims.

55 A structure constituting one embodiment

of the invention is illustrated in the accompanying drawings forming a part of the specification in which:

Figure I is a vertical section through a machine embodying the invention. 60

Figure II is a horizontal sectional view taken on line II—II of Figure I, with a portion of the work retaining member broken away to more clearly illustrate the mounting of the rollers for supporting said 65 member.

Figure III is an enlarged sectional elevation taken on line III—III of Figure II and

Figure IV is a detailed sectional elevation 70 illustrating a slightly modified form of the invention.

Like reference characters throughout the several views of the drawings indicate corresponding parts. 75

It has been found desirable in providing mechanism for properly grinding and polishing the outer surfaces of the rollers to employ a pair of eccentrically mounted and oppositely driven rotating members and it 80 is also found desirable to rotate them in opposite directions at different rates of speed in such a manner as to bear against the opposite surfaces of the rollers to be ground or polished and in thus performing the 85 grinding and polishing operation the uniformity and precision of the finished product is found to be greatly increased. By providing means upon one of said members for suitably retaining the rollers or work 90 in position between the same the number of parts of the machine is considerably reduced and the shifting or sliding of the work is effected by the eccentric mounting of said members, one with respect to the 95 other. It will be readily understood upon inspection of the accompanying drawings that by thus mounting the work retaining member in such a manner as to move with and be moved by the member for supporting the work that said retaining member will move in a path eccentric to the path of movement of the upper grinding member, but will at the same time be free to rotate independently thereof by reason of 100 the rotation of the upper and lower members in opposite directions at different rates of speed. The movement thus imparted to the rollers will insure the forming of the outer surfaces thereof in a uniform manner 105

110

to produce a smooth and perfectly formed surface upon each roller.

In the embodiment of the invention illustrated herewith 1 indicates a base frame in the form of a casing provided with an offset outwardly extending arm 2 which is adapted to support the bearing sleeve 3 positioned in alignment with a similar bearing sleeve 4 carried by the main portion of the frame 10 and a shaft 5 is rotatably supported by said bearings and extends within the inner portion of the base frame for a purpose to be hereinafter described. Positioned above the shaft 5 is a bearing sleeve 6 which is suitably supported by the main frame portion 1 and the bearing 6 supports a rotatable shaft 7 having one end thereof extending within the interior portion of the casing. A drive pulley 8 of the usual construction is mounted upon and firmly secured to the shaft 5 in such a manner as to impart rotation thereto through the usual driving belt (not shown). An idler pulley 9 of the same diameter as the pulley 8 is mounted adjacent the pulley 8 in such a manner as to permit the driving belt to be forced thereon when for any reason it is desired to disconnect the operating parts of the mechanism from the power belt. Secured to the shaft 5 in any desired manner is a gear 10 which is adapted to mesh with a gear 11 firmly secured to the outer end of the shaft 7 in any preferred manner. The gears 10 and 11 are of different sizes and while in the embodiment illustrated herewith the gear 11 is of larger diameter than the gear 10, it is to be understood that the gears may be removed and others substituted therefor so as to increase or decrease the relative difference in sizes of the gears as shown, or the gears may be transposed so that the gear carried by the shaft 5 will be of greater diameter than the gear carried by the shaft 7. By forming the gears 10 and 11 of different diameters, gears 12 and 14 being equal and gears 13 and 15 being also equal, one of the members between which the work is disposed is driven at a greater speed than the other, thus imparting to the work retaining member a rotating movement. Mounted upon the inner end portion of the shaft 5 is a bevelled gear 12 which is connected with a bevelled gear 13 for rotating the upper grinding member while in a similar manner the bevelled gear 14 is mounted upon the inner end of the shaft 7 and is connected with the bevelled gear 15 for rotating the work supporting member. By reason of the fact that the shafts 5 and 7 rotate in opposite directions, rotation will be imparted to the upper and lower work engaging members in such a manner as to rotate the same in opposite directions. Means for raising and lowering the vertical shaft 16 and the parts superimposed thereon which are driven

by the gear 13 is shown in the lower part of the casing beneath said gear 13 but as this mechanism has been previously described in one of my co-pending applications above referred to, it is not believed to be necessary to give a detailed description of the same in the present application. The bevel gear 15 is firmly secured to the lower end portion of a sleeve 17 which is rotatably mounted within the upper portion of the frame and said sleeve has firmly secured to the upper end thereof an eccentric 17' disposed within the hub 18 of a dished plate 18' which is rotatably supported by the base frame through the anti-friction bearings 19 and 20, the latter of which is eccentrically mounted with respect to the former, said bearings being separated by a plate 21 having recesses in its upper and lower faces to receive said bearings as indicated in Figure I. The bearing 20 in addition to being eccentric to the bearing 19 is also eccentric to the shaft 16. The dished plate 18' which is supported by the anti-friction bearings 19 and 20 and driven by the sleeve 17 carries a ring 22 upon which is mounted an annular member 23 which is threaded externally at 24 to receive a ring 25 for supporting a plurality of rollers 26 provided with ball bearings 27 supported by a shaft 28 which is screw threaded at 29 into the ring 25 as indicated in Figure III. The roller 26 and bearing 27 is held upon the shaft by means of a plate 30 lying within the recessed portion 31 of the roller, said plate being secured by means of a stud 32 screwed into the outer end of the shaft 28. The ring 25 is preferably split as indicated at 33 and is provided on its adjacent ends with lugs 34 adapted to receive the adjusting screw 35 for tightening the ring upon the annular member 23. Positioned upon the upper surface of the annular member 23 is a removable ring 36, the upper surface of which is in one embodiment of the invention inclined as indicated at 37 a sufficient amount to bring the upper surface of the tapered roller 38 in parallel relation with the horizontally disposed grinding surface 39 of the grinding ring 40 which is suitably connected with and driven by a plate 41 connected with the dished plate 42 supported upon and driven by the upright shaft 16 by being keyed or otherwise connected therewith. A suitable number of weights 43, 44 and 45 are superimposed upon the dish shaped plate 42 to cause the grinding ring or member 40 to be held firmly in contact with the rollers to be ground which travel upon and are supported by the lower work carrying ring as shown in Figures III and IV. A retaining ring 46 is provided for holding the rollers in proper position between the grinding ring 40 and supporting ring 36, said retaining ring being held against displacement by the flanges 125 130

47 on the supporting rollers 26 as indicated in Figure III. The tapered rollers 38 lie within recesses 48 formed in the retaining ring 46, the rollers being free to rotate within said recesses when the supporting ring 36 is rotated in one direction and the grinding ring 40 in the opposite direction. A recess 49 is formed within the supporting ring 36 beneath the rollers 38 to receive suitable material for lubricating the rollers during grinding. The tapered rollers 38 are held against lateral movement upon the supporting ring 36 by means of the retaining ring 46 but are constantly moved laterally upon the grinding surface 39 of the upper grinding ring 40 by reason of the fact that the supporting ring 36 is eccentrically mounted. Since the tapered rollers 38 are carried upon the bevelled or inclined surface 37 of the supporting ring 36, the upper surfaces of said rollers are at all times parallel with the horizontally disposed grinding surface 39 of the ring 40, thereby assuring the grinding of the rollers to the proper taper, which is maintained by previously grinding the surface 37 of the supporting ring 36 at the proper predetermined angle to suit the taper of the roller to be ground.

In the modification shown in Figure IV the rollers 50 for supporting the retaining ring 46 are made adjustable to be moved up and down for raising and lowering the retaining ring to take care of rollers of different sizes, said adjustment being effected by making the shaft 51 carrying the anti-friction bearing 52 in the form of a crank shaft, the outer portion being eccentric to the stud portion 53, said stud extending through and being clamped upon the retaining ring 54 by means of the nut 55 which when loosened, will permit the shaft 51 to be rotated so as to either elevate or lower the roller 50 according to whether it is desired to raise or lower the retaining ring 46. When the roller 50 has been moved to the desired position the nut 55 is tightened to clamp the roller upon the ring 54. The anti-friction bearing 52 of the roller is held within the recess 56 thereof by means of the plate 57 which is secured upon the shaft 51 by means of the stud 58, said parts being constructed in a similar manner to the corresponding parts shown in Figure III. In this modification I have shown the upper surface of the work supporting ring 59 parallel with the lower surface of the ring 40 to accommodate the rollers 60 having straight sides.

It will be apparent to those skilled in the art that the invention shown and described herein is susceptible to various modifications, embodiments and arrangements to suit special or varying conditions and I wish it to be understood that the terms which I have used are merely descriptive and not limiting and that it is my intention to include any

and all modifications which come within the scope of the invention as defined in the appended claims.

What I claim as new and desire to cover by Letters Patent is:

1. In a grinding machine for tapered rollers, a frame, a grinding ring, a roller supporting ring, means for mounting said rings on said frame to revolve about a common axis, one of said rings being arranged eccentrically to said axis, and means carried by said supporting ring for assisting it to move the rollers across the face of said grinding ring when said supporting ring is rotated. 75

2. In a grinding machine for tapered rollers, a frame, upper and lower eccentrically mounted members carried by said frame, between which said rollers are disposed, one of said members having an inclined surface forming a seat for the rollers, a retaining ring having recesses in which said rollers are disposed and a series of supporting and guiding rollers for said retaining ring having vertical flanges adapted to prevent displacement of the retaining ring. 80 85

3. In a grinding machine for tapered rollers, a frame, upper and lower eccentrically mounted members carried by said frame, one of said members having an inclined face forming a seat for the rollers, means for rotating said members in opposite directions, a retaining ring for the rollers and a series of supporting and guiding rollers for said ring having flanges adapted to prevent displacement of the ring. 90 95

4. In a grinding machine for tapered rollers, a frame, upper and lower rings carried by said frame between which the rollers are disposed, one of said rings having an inclined surface forming a seat for the rollers, means for rotating the rings at different rates of speed, a freely rotatable ring serving to hold the rollers between said rings and supporting means for said last mentioned ring located outside of the path of movement of said first rings. 100 105 110

5. In a grinding machine for tapered rollers, a frame, upper and lower rotatable annular members carried by said frame, between which the rollers are disposed, one of said members being eccentrically mounted relative to its axis of rotation and having an inclined surface forming a seat for the rollers, means for imparting movement to said one member and freely rotatable means supported exteriorly of said upper and lower members for retaining the rollers in position therebetween. 115 120

6. In a grinding machine for tapered rollers, a frame, upper and lower members supported by said frame, upon the adjacent faces of which the rollers are disposed, one of said faces being inclined with respect to the other, a retaining ring rotatably mounted on one of said members for holding the 125 130

rollers between said members, means for rotating one of said members in one direction at a given rate of speed and means for rotating the other of said members in an opposite direction at a different rate of speed and simultaneously imparting lateral movement thereto.

7. In a grinding machine, a frame, upper and lower spaced members carried by the frame, upon the adjacent faces of which the objects to be ground are disposed, means for rotating said members in opposite directions at different rates of speed, a retaining member for said objects, a vertically adjustable ring carried by one of said spaced members and a plurality of supporting and guiding rollers for said retaining member carried by said vertically adjustable ring.

8. In a grinding machine, a frame, upper and lower spaced members carried by the frame, upon the adjacent faces of which the objects to be ground are disposed, means for rotating said members in opposite directions at different rates of speed, a retaining member for said objects, a vertically adjustable ring carried by one of said spaced members, a plurality of supporting and guiding rollers for said retaining member carried by said vertically adjustable ring and means for locking said ring against accidental displacement.

9. In a grinding machine, a frame, upper and lower spaced members carried by the frame, upon the adjacent faces of which the objects to be ground are disposed, means for rotating said members in opposite directions, a retaining member for said objects, a ring adjustable upon one of said spaced members, a plurality of rollers disposed upon said ring and adapted to support said retaining member and flanges upon the rollers arranged to prevent accidental displacement of said retaining member.

10. In a grinding machine, a frame, upper and lower spaced members carried by the frame, upon the adjacent faces of which the objects to be ground are disposed, means for rotating said members in opposite directions at different rates of speed, a retaining member for said objects, a plurality of rollers for supporting and guiding said retaining member and eccentrically mounted supports for said rollers adapted to be rotated for the purpose of adjusting the height of the rollers to raise or lower said retaining member.

11. In a grinding machine, a frame, upper and lower spaced members carried by the frame, upon the adjacent faces of which the objects to be ground are disposed, means for rotating said members in opposite directions at different rates of speed, a retaining member for said objects, a plurality of rollers for supporting and guiding said retaining member, anti-friction bearings for said

rollers and a plurality of shafts for supporting said anti-friction bearings connected with one of said spaced members.

12. In a grinding machine, a frame, upper and lower spaced members carried by the frame, upon the adjacent faces of which the objects to be ground are disposed, means for rotating said members in opposite directions at different rates of speed, a retaining member for said objects, a plurality of rollers for supporting and guiding said retaining member, anti-friction bearings for said rollers, a plurality of crank pins upon which said anti-friction bearings are journaled and means for clamping said crank pins in different positions of adjustment upon one of said spaced members.

13. In a grinding machine, a frame, upper and lower spaced members carried by the frame, upon the adjacent faces of which the objects to be ground are disposed, means for rotating said members in opposite directions at different rates of speed, a retaining member for said objects, a plurality of rollers for supporting and guiding said retaining member, anti-friction bearings positioned within said rollers, crank-shafts upon which said bearings are journaled, said crank shafts being rotatably connected with one of said spaced members, a screw threaded in the outer end of each of said crankshafts and a plate held by each of said screws to prevent displacement of said bearings.

14. In a grinding machine, a frame, a grinding member and a work carrying member carried by said frame, a work retaining ring having a portion between said members, and means for supporting said retaining ring from said work carrying member comprising a series of rollers arranged exteriorly of said member, and means for varying the position of said ring relative to said members.

15. In a grinding machine, a frame, a grinding member and a work carrying member carried by said frame, a work retaining ring, and a ring adjustably mounted on said work carrying member having a plurality of supporting and guiding rollers for holding said retaining ring in various positions of adjustment relative to said members.

16. In a roller grinding machine, a frame, an upper grinding member, a lower roller supporting member, a retaining ring having a series of apertures for receiving rollers to be ground and having a portion between said members, a ring adjustably mounted on said supporting member, and rollers carried by said latter ring for supporting said retaining ring whereby the spacing of said retaining ring relative to said members may be varied.

17. In a roller grinding machine, a

- frame, an upper grinding member, a lower roller supporting member, a retaining ring having a series of openings for receiving rollers to be ground and having a portion 5 between said members, a ring adjustably mounted in said supporting member, and a series of rollers individually adjustably mounted on said latter ring for supporting and guiding said retaining ring.
- 10 18. In a grinding machine, a frame, a grinding member mounted therein, a work supporting ring opposite said grinding member, and means for mounting said ring on said frame to revolve on an axis 15 eccentric to said ring.
19. In a grinding machine, a frame, a grinding member carried thereby, a work supporting ring opposite said grinding member, means for revolvably mounting 20 said ring on an axis eccentric thereto, and a retaining ring carried by said supporting ring having apertures for receiving the work.
20. In a roller grinding machine, a frame, 25 a grinding member rotatably mounted thereon, a roller supporting ring opposite said grinding member, means for mounting said ring to revolve on an axis displaced from the center of the ring and in aline-
- ment with the axis of rotation of said 30 grinding member, and a freely rotatable roller retaining ring carried by said supporting ring.
21. In a roller grinding machine, a frame, a grinding ring rotatably mounted thereon, 35 a roller supporting ring adjacent the grinding face of said grinding ring, means for mounting said roller supporting ring to revolve on an axis displaced from the center thereof but coincident with the axis of rotation of said grinding ring, a roller retaining ring supported by said roller supporting ring to be freely rotatable thereon, and means whereby said grinding ring and 40 said roller supporting ring may be rotated 45 in opposite directions.
22. In a grinding machine, a frame, a grinding member mounted thereon, a base ring upon which the work is superimposed 50 mounted opposite said grinding member, and means for mounting the base ring to rotate about an axis which revolves in a path eccentric to the axis of rotation of the grinder.

In testimony whereof, I affix my signature. 55

HANS LUTZ.
